APPARATUS FOR VAPORIZING AND SUPER-HEATING HYDROCARBON OILS

Gilbert D. Dill, Wilmette, Ill., assignor to Herman A. Brassert, New York, N. Y.

Application May 25, 1940, Serial No. 337,115 (C.I. 196—108)

1 Claim.

This invention relates to means whereby a hydrocarbon oil may be heated in a tube or tubes to temperatures considerably above the vaporizing temperature of the oil and above the cracking temperatures of many of the constituents thereof and may also be delivered to the point of use without liability to clogging of the tube or tubes by carbon deposition, thus making possible the effective preheating of hydrocarbons and a consequent wider field of utility.

The invention aims particularly to provide apparatus for so vaporizing and so superheating the vapor of a hydrocarbon oil that, without carbon deposition in the vaporizing and superheating step, there may be provided at the point of use a superheated vapor having many of the physical characteristics of a fixed gas.

Not only is substantial preheating of a vaporized hydrocarbon desirable when undertaking to obtain as large heat releases as possible per cubic unit of combustion space but such preheating is also desirable when the hydrocarbon is to form one of the reagents of a chemical reaction, such as the reduction of a metallic oxide. Heretofore substantial preheating, that is, preheating extending into the field of superheating, has usually been attended with so much deposition of carbon in the preheating apparatus as to require frequent cleaning or replacement, and thus preheating to the desired extent of the hydrocarbon alone has not usually been possible. The principal difficulty heretofore encountered in attempts to effect substantial preheating of a hydrocarbon, without admixture therewith of some other substance, has been the inability to avoid excessive local heating, with the resultant decomposition of the hydrocarbon in the region of the local heating and the deposition of the carbon on the overheated surface.

The present invention aims to overcome the difficulties heretofore encountered in effective preheating of the vapors of hydrocarbon oils by avoiding excessive local heating. To this end the invention aims to effect such a rapid movement of the hydrocarbon through the tube or tubes and such a turbulence in the tubes that the duration of contact of the hydrocarbon with the heated tube wall at any one point in its path of travel is short but yet sufficient and frequent enough to effect a substantially uniform heat exchange throughout the path of travel, thereby preventing the tendency of any part of the tube to become overheated while at the same time preventing conduction from the tube to any of

the particles of the fluid of an excessive amount of heat.

The invention aims further to provide for substantially constant wetting of the tube surfaces to provide against overheating and yet to avoid full tube operation at any point throughout the heating zone, thereby preventing geyser action and local zones in which there is no wetting agent, with the resultant formation of local hot spots, etc. To this end the invention contemplates introducing into the input, into the preheating tube or tubes a part of the already vaporized hydrocarbon, in order to accelerate the movement of the hydrocarbon through the heating tube, to insure turbulence in the tube and to provide that the stream flowing through the tube shall be a combined stream of a flowing vapor and a flowing liquid, the liquid being to a large extent entrained by the vapor and partaking of the turbulent movements thereof, so that it will repeatedly and rapidly be brought into and out of contact with the walls of the tube. The invention also contemplates the preheating of the liquid by condensation of a part of the entering stream of vapor therein.

Other objects and important features of the invention will appear from the following description and claim when considered in connection with the accompanying drawing, in which the figure is a diagrammatic view showing apparatus embodying the present invention.

In the illustrative embodiment of vaporizing and preheating apparatus, the heating chamber or furnace 2 is shown as provided with burners 4 located in a refractory support 6. The flame from each burner projects into the central combustion space 8 bounded by the refractory and also extends somewhat up into the combustion space 10 which is bounded by the inner coil 12 of the tube in which the heating of the hydrocarbon is effected and through which it circulates. The outer coil 14, although located in the heating chamber 2, is shielded from the radiant heat of the flame by the inner coil 12 which is a continuation of the outer coil 14. These coils may rest upon and be partly supported by the refractory 6. The products of combustion pass out through the stack 16.

As shown in the drawing, the hydrocarbon oil to be vaporized and superheated passes through the outer coil 14 before it enters the inner coil 12 in the heating chamber, the outer coil 14 having an extension 18 outside the chamber 2 into which the hydrocarbon oil is forced by a pump 20 that receives it from a storage or supply tank 22.

The oil, after it has passed through the outer coil 14 and through the inner coil 12 and has been vaporized and superheated, passes out of the heating chamber through the extension 24 of the inner coil 12. The extension 24 has two branches, one of which, 26, conducts the vaporized and superheated hydrocarbon to the point of use, for example, to a reaction apparatus of the type disclosed in my co-pending application Serial No. 244,612, filed December 8, 1938. The other branch 28 constitutes a by-pass connecting the output extension 24 of the inner coil 12 with the input extension 18 of the outer coil 14. Located in the by-pass 28 is a valve 30 for controlling the amount of superheated vapor to be by-passed from the output extension 24 into the input extension 18 and also the pressure drop through the by-pass. If additional pressure drop is desired the by-pass 28 may connect with a venturi 29 in the input 14, as shown. The venturi also contributes to setting up of turbulence in the combined stream of vapor and liquid.

By providing the by-pass 28, with its controlled valve 30, a part of the vaporized and superheated hydrocarbon may be introduced into the liquid hydrocarbon which is being forced into the outer coil 14 through its extension 18 by the action of the pump 20. The superheated vapor is introduced in a sufficient amount in respect to its contained heat, so that it will not be condensed in the liquid but will sweep along with the liquid hydrocarbon, as it enters the outer coil 14, as a combined stream of vapor and liquid. The vapor and liquid will sweep through the coil 14 together, the liquid being in a sense entrained in the vapor stream which results from its rapid flow. It will be seen that the pressure built up by the vaporization of the hydrocarbon in the coils 12 and 14, and particularly in the coil 12, will provide the desired pressure drop for obtaining the desired velocity of flow of the vaporized hydrocarbon through the by-pass 28 and the outer coil 14 as well as through the inner coil 12.

In this manner a relatively high velocity of flow may be maintained of the combined stream of liquid and vapor and a very high degree of turbulence, the velocity being preferably from 900 feet per minute up, as required by the nature of the particular hydrocarbon which is being vaporized and superheated.

As hereinabove suggested, the turbulence which results from the high velocity and from the fact that the stream of fluid entering the heating coils is a combined stream made up of a stream of vapor and an entrained stream of liquid and that therefore the liquid partakes of the high turbulence of the vapor, not only insures a constant wetting of the tubes and therefore the prevention of hot spots, but insures short but rapidly repeated contacts of the particles of the fluid with

the tube, thus preventing overheating of any particles while at the same time providing the desired heating. Moreover, the wiping action due to the high velocity, the turbulence, etc., prevents deposition in the tubes of any carbon that might otherwise be deposited from such decomposition as may take place.

As a result of the construction and arrangement of the vaporizing and preheating apparatus 10 and of the novel method of effecting the circulation and preheating, it is possible, by the utilization of the present invention, to obtain preheats of hydrocarbons, without carbon deposition in the preheating tubes, which are in the range of superheats and far above the cracking temperatures of most of the constituents of the hydrocarbon oil and thus deliver at the point of use a superheated hydrocarbon vapor having many of the physical characteristics of a fixed gas. The process and apparatus thus permits a wider use of hydrocarbons in industrial processes, such as the carbon impregnation or coating and reduction of metallic oxides, and also makes possible higher heat releases per unit of combustion space with oil burners.

In the use of the apparatus of the present invention with some of the heavier grades of oil, such as "Bunker C," it is sometimes advantageous to introduce steam, as well as vaporized hydrocarbon, into the stream of unvaporized oil entering the vaporizing and superheating coils 14 and 12, the function of the steam in such cases being well understood in the art. The steam may be introduced through the valve controlled in 35 take 32 into the by-pass 28.

What is claimed as new is:

Apparatus for vaporizing and superheating a hydrocarbon oil comprising, in combination, a source of radiant and convection heat, a continuous coil exposed to the heat from said source of heat, said coil comprising a section exposed to the radiant heat of said source and a section substantially shielded by the aforementioned section from said radiant heat but still exposed to the convection heat, means for forcing hydrocarbon oil to be vaporized into and through said coil, said means being connected to said coil in such manner that it delivers the oil first to the section of the coil that is shielded from the radiant heat, and a by-pass between the discharge and the intake ends of said coil for reintroducing into the intake end of said coil and mixing with the stream of unvaporized hydrocarbon oil entering said intake end a portion of the vaporized and superheated hydrocarbon oil issuing from the discharge end of said coil, a venturi being provided in the intake end of said coil and said by-pass being connected with the low pressure region of said venturi.
